UNITED STATES PATENT OFFICE.

HENRY T. PAISTE, OF PHILADELPHIA, PENNSYLVANIA.

ROSETTE.

SPECIFICATION forming part of Letters Patent No. 682,114, dated September 3, 1901.

Application filed October 20, 1900. Serial No. 33,736. (No model.)

To all whom it may concern:

Be it known that I, HENRY T. PAISTE, a citizen of the United States, residing in Philadelphia, Pennsylvania, have invented certain 5 Improvements in Rosettes, of which the following is a specification.

My invention relates to certain improvements in that class of electrical fixtures known as "rosettes," and has for its object the 10 vision of means which shall prevent the two halves of the same from coming apart when said rosette is subjected to vibration. This object I attain as hereinafter set forth, reference being had to the accompanying drawings, in which—

Figure 1 is a detached perspective view of the two halves of the rosette to which my invention is applied; and Fig. 2 is a cross-sectional view through a rosette at the terminals 20 thereof, showing the detail structure of my improvement.

One of the objections to rosettes of the forms at present manufactured has been that whenever they were used in places in which there 25 was any vibration the lower half would sooner or later work loose and finally become detached from the fixed half. As it will be understood by those familiar with the construction of these fixtures, this is but the natural 30 consequence of the design of the rosette, and it is believed that the device herein described completely overcomes this fault.

In the drawings, A is the upper half or base of a rosette, preferably made of porcelain 35 and having holes *a a*, through which pass the screws used for fastening it to a ceiling or other support. Terminals C, having a slot *e* and a screw *e'* for holding and tapping an electric feed-wire, are held in appropriate recesses in the porcelain by screws *c*, said screws also serving to attach the U-shaped clips D. These clips, besides being used to hold the 40 lower half of the rosette to the upper half, also form electrical contact with the terminal C and are made with projections *d* on their upper outside edges, which serve as stops.

B is the lower half or cap of the rosette, also formed of porcelain and having a hole E in the middle of its lower face. Within it 45 are four sets of terminals, in the present instance about ninety degrees apart. Two of the terminals are arranged opposite one an-

other and are U-shaped, forming hooks F, which are placed so as to engage with the clips D of the upper half A of the rosette and hold the cap B thereto when the same is turned. These clips have screws *g* for the connection of a fuse-wire. Tubular screws *f* pass through holes *f'* in the porcelain cap B and secure the terminals F F to the said cap. 55 The screws *f* are also threaded internally and have passing through them screws *h*, constructed to fit this inside thread. A second pair of terminals I I are held in place by screws *i*, and have other screws *q* and *p* for 60 the attachment of a fuse-wire and connections leading out through the hole E, respectively.

In putting the two halves of the rosette together the part B is brought into contact with 70 the part A and given a rotary motion. This causes the hooks F to engage the clips D, the rotation being stopped when the hooks F strike a projection *d*. The screws *h* are now set up and, striking the lower part of the 75 clips D, clamp them firmly to the hooks F. This not only prevents the cap B from turning and becoming detached from the base A, but also insures good electrical contact between the terminals and the clips. 80

I claim as my invention—

1. The combination in a rosette, of a base, a cap, means for coupling the cap to the base and one or more screws extending through the cap and bearing upon the said coupling 85 means, substantially as described.

2. The combination in a rosette, of a base and a cap, means for removably attaching the cap to the base by a rotary motion of the cap, and means operated from outside of the 90 said rosette and applied to the means for holding the cap to the base, whereby the cap may be rigidly retained on the base after they have been removably connected, substantially as described. 95

3. The combination in a rosette of the character described, of a base, clips thereon, a cap for said base, hooks on said cap constructed to engage the clips on the base and a device operated from the outside of said 100 rosette for clamping the hooks and clips together, substantially as described.

4. The combination in a rosette, of a cap, hooks thereon, a base, a set of clips on the

base, said hooks arranged to engage the clips whereby the cap may be detachably connected to the base, screws for clamping the clips to the hooks whereby the cap may be 5 rigidly connected to the base, substantially as described.

5. The combination in a rosette of the character described, of a base-piece, a clip thereon, a cap, a terminal on said cap constructed to engage the clip on the base-piece, a tubular screw holding the terminal to the cap and a screw fitting the interior of said tubular screw and adapted to clamp the clip on the base to the terminal on the cap, substantially as described.

6. In a rosette of the character described, the combination of a base, electrical terminals on said base, U-shaped clips connected to said terminals, a cap, U-shaped hooks thereon, said hooks being held to the cap by the hollow screws, a second screw passing through each of the hollow screws and con-

structed to clamp the clips on the base to the hooks on the cap, a third screw on each hook of the cap, electrical terminals also on the cap and screws on said terminals, substantially as described.

7. The combination of a base, a cap constructed to fit on said base, clips on the base, and hooks on the cap engaging the clips whereby the cap is held to the base, a tubular screw having a slotted head and extending from the outside through the cap into each hook, screws extending through the tubular screws and arranged to engage the clips of the base 35 when the cap and the base are put together, substantially as described.

In testimony whereof I have signed my name to this specification in the presence of two subscribing witnesses.

HENRY T. PAISTE.
